UNITED STATES PATENT OFFICE.

HARRY H. MOMYER, OF DALLAS, TEXAS.

MOVING-PICTURE MACHINE.

1,111,229.

Specification of Letters Patent. Patented Sept. 22, 1914.

Application filed February 26, 1913. Serial No. 750,899.

To all whom it may concern:

Be it known that I, HARRY H. MOMYER, a citizen of the United States, residing at Dallas, in the county of Dallas and State of Texas, have invented certain new and useful Improvements in Moving-Picture Machines, of which the following is a specification, reference being had to the accompanying drawings.

10 This invention comprehends certain new and useful improvements in moving picture machines and has for a primary object to generally improve the parts of the machine and to provide means for moving the projector to correspond with the movement of the film, thus making the pictures clearer.

Another object is to generally improve and simplify the construction and operation of the various parts of the machine and provide means for readily adjusting the film guiding means, whereby the film may be adjusted with respect to the lens within the projector.

With the above and other objects in view, 25 this invention consists in the novel features of construction, and in the combination and arrangement of parts hereinafter more fully described, pointed out in the claims and shown in the accompanying drawings, 30 in which:

Figure 1, is a view of the complete machine in side elevation. Fig. 2, is a front elevational view thereof. Fig. 3, is an enlarged detail horizontal cross sectional view 35 through the projector and its guide strips, said view being taken on the line 3—3 of Fig. 4. Fig. 4, is an enlarged detail vertical cross sectional view on the line 4—4 of Fig. 1. Fig. 5, is a detail elevational view of the 40 shutter.

Referring more specifically to the drawings in which similar reference characters designate corresponding parts; 1 designates the base supported by the legs 2 at its corners and having the lantern box 3 positioned upon its rear end while the standard 4 projects upwardly from one of the forward corners of the base and supports the reel 5 from which the film 6 is fed, said reel being rotatably mounted upon the shaft 7 carried in the upper end of the standard 4. The receiving reel 8 is mounted upon a shaft 9 carried in the lower end of the standard 4, beneath the base 1, and the reel 8 receives the

film 6 after the latter has passed between the 55 guide strips 10 and 11 adjustably positioned between the lantern box 3 and the movable projector 12. The upper ends of the front guide strips 10 are curved outwardly while the corresponding ends of the rear guide 60 strips 11 are curved rearwardly to eliminate all danger of tearing the film as the latter is fed between said strips. The lower ends of the guide strips 10 and 11 are also separated to prevent tearing the film as it leaves 65 said strips. The guide strips 10 and 11 are secured to the forward standards 13 which are connected at their upper ends by the cross member 14, the lower ends of the standards 13 being secured to the movable 70 carriage 15 which may be adjusted longitudinally of the base 1 by rotating the wheel 16 upon the shaft 17 which has pinions 18 mounted thereon and engaged with the racks 19 upon the base 1, as will be readily 75 understood. The curvature of the ends of the guide strips 10 and 11, inwardly of their turned extremity may be regulated by the bolts 20 and 21, the bolts 20 being positioned through the cross member 14 while the bolts 21 are positioned through the lower cross member 22 connecting the lower ends of the standards 13.

The longitudinal shaft 23 is rotatably engaged through the upper cross member 14 85 and through the cross member 24 projecting from the side of the standard 4. A lower cross member 25 is secured to the base 1 with one end engaged against the standard 4 and said cross member 25 is parallel with the 90 cross member 24. The rear faces of the cross members 24 and 25 are curved and have the opposite ends of the vertically extending projector guide strips 26 secured thereto by means of the bolts 27 and 28, respectively, 95 the strips 26 being in spaced relation to one another and having slight movement between the curved faces of the cross members 24 and 25 and the heads of their respective belts 27 and 28. The projector 12 is provided with vertical slots 29 in the opposite sides of its wide portion 12' to accommodate the guide strips 26 and permit the projector to slide vertically between the guide strips. The strips 26 and the slots 29 are 105 curved to correspond, thus permitting the projector to move in an arc and as said projector, which carries the forward or, pro-

jected lens 30 in the usual manner, moves downwardly with each picture, a steady focus is retained for each picture thrown upon the screen, the curvature of said strips 5 26 and slots 29 depending upon the distance between the projector and the screen, as will be clearly understood.

The projector 12 has an extension 31 upon its rear upper edge and extending upwardly 10 and engaged with the cam wheel 32 upon the shaft 23, which cam wheel serves to force the projector 12 downwardly with each picture. The extension 31 is retained in engagement with the cam wheel 32 and the 15 projector automatically returned to normal position after each picture, by means of the springs 33 and 34, the spring 33 being secured by one end to the projector outwardly of the guide strips 26 while its opposite end 20 is secured to the cross member 24. The spring 34 has one end secured to the lug 35 extending rearwardly from the projector 12 while the opposite end of the spring is secured to the base 1.

25 The rotary shutter 36 is carried upon the rear end of the shaft 23 while the belt wheel 37 is carried upon the forward end of the shaft and has the belt 38 engaged therearound, by means of which belt the shaft 30 23 is rotated.

The belt 38 passes around a series of rollers 39 between the belt wheel 37 and the large pulley 40 on the shaft 41 upon which the pulley 42 is mounted, said pulley 42 being driven by the belt 43 from the drive 35 pulley 44 upon the drive shaft 45. The shafts 41 and 45 are mounted in the adjustable frame 46 which is pivoted at its forward end to the lugs 47 depending from the 40 forward end of the base, by means of the shaft 48 mounted through the lugs 47 and carrying certain of the rollers 39. The adjustable frame 46 is retained in adjusted position by means of the latch member 49 45 carried upon the transverse rod 50 positioned through the rear end of the frame 46 and having the wheel 51 upon one end by means of which the rod may be turned to engage the latch member 49 with the curved 50 depending arm 52 secured at its upper end to the base 1 beneath the lantern box 3. The shaft 41 also carries the roller, (not shown) for feeding the film 6. It will be understood that the adjustable frame 46 is raised and 55 lowered and secured in adjusted position by the latch member 49 to adjust the picture on the screen. The receiving reel or take up reel 8 for the film 6 is driven by a separate belt 53 passing around a belt wheel 54 upon the shaft 9 and around one of the rollers 39, 60 as will be clearly understood.

From the foregoing it will be apparent that I have provided a moving picture ma-

chine in which the pictures may be focused on the screen by adjusting the carriage 15 to 65 move the film, instead of adjusting the lens. The machine is also constructed so that the projector and lens carried thereby will have a motion corresponding to the movement of each picture upon the film during the time 70 it is projected upon the screen, thus retaining the same in focus and thereby making the picture clear. Further, the reciprocating movement of the projector is caused by a cam carried upon the same shaft as the 75 rotary shutter and owing to the construction and arrangement of the various parts of the machine, the same may be readily adjusted, as desired, and retained in adjusted 80 position. The film may be readily adjusted upon the screen by adjusting the frame 46 to bring the picture on the center of the screen as will be clearly understood by referring to the drawing.

Owing to the extremely simple construction and arrangement of the parts of the machine, the cost of the same will be reduced and the machine will be highly efficient and durable in use.

While I have shown the preferred embodiment of my invention, it will be apparent that minor changes in the details of construction may be made within the scope of the appended claims without departing from the spirit of my invention.

Having thus described my invention, what I claim is:—

1. A moving picture machine comprising a base, a longitudinal shaft mounted above the base, a rotary shutter upon one end of the shaft, a pulley upon the opposite end of the shaft, a cam wheel mounted upon the shaft, a projector mounted above the base and engaged with the cam wheel, means for feeding a film rearwardly of the projector, 100 a lantern box rearwardly of the film and shutter, the cam wheel causing the projector to move downwardly with each picture upon the film, means for causing upward movement of the projector at the end of each picture projection, and means for driving the pulley.

2. A moving picture machine comprising a base, means for supporting the base, a longitudinal shaft above the base, a cam 115 wheel upon the shaft, a shutter upon the shaft, a pulley upon the shaft, film guides upon the base, means for adjusting the film guides longitudinally of the base, film reels mounted above and below the base, a frame 120 pivoted at one end beneath the base, means for retaining the frame in adjusted position, a film feed roller mounted in the frame, a movable projector mounted above the base and engaged with the cam wheel, drive pulleys carried by the frame, connections be-

tween certain of said drive pulleys and the pulley on the longitudinal shaft to rotate the shutter and cam wheel and cause the latter to move the projector in one direction,
5 a lantern box rearwardly of the shutter, and means for returning the projector to normal position.

In testimony whereof I heretnto affix my signature in the presence of two witnesses.

HARRY H. MOMYER.
